UNITED STATES PATENT OFFICE.

JAMES A. MURPHY, OF HOLYOKE, MASSACHUSETTS, ASSIGNOR OF ONE-HALF TO GEORGE NIGHTINGALE, OF HOLYOKE, MASSACHUSETTS.

MAILING-TUBE.

No. 901,305.

Specification of Letters Patent.

Patented Oct. 13, 1908.

Application filed February 2, 1908. Serial No. 413,979.

To all whom it may concern:

Be it known that I, JAMES A. MURPHY, a citizen of the United States of America, residing at Holyoke, in the county of Hampden 5 and State of Massachusetts, have invented new and useful Improvements in Mailing-Tubes, of which the following is a specification.

This invention relates to mailing tubes, the 10 object of the invention being to provide a tube of this character in which one end of the papers, or like articles to be inclosed therein, may be inserted in a slit which divides the wall of the tube longitudinally, an inclosing 15 wrapper being permanently attached to the tube in which the latter may be rolled, means being provided to secure the end of the wrapper to the tube.

The invention is illustrated in the accompanying drawing, in which,—

Figure 1 is a plan view of a tube and wrapper, the latter being in its unrolled position, a portion of the structure being broken away, this view also showing a paper or like article 25 with its end inserted in the slotted tube. Fig. 2 is an end elevation of the tube and wrapper shown in Fig. 1. Fig. 3 is an elevation of that side of the tube showing the slit therein to receive the article to be inclosed, the wrapper 30 being shown in section, the plane of which is substantially on line 3—3, Fig. 2. Fig. 4 is a plan view similar to Fig. 1 showing a wrapper provided with a gummed edge instead of the mechanical fastening device of 35 Fig. 1. Fig. 5 is an end view of a tube inclosed in its wrapper with the end of the latter secured by means of the mechanical fastening device shown in Fig. 1.

Referring now to these drawings, *a* indicates an ordinary mailing tube of paper or 40 some similar material, circular in cross section, and having permanently attached thereto by means of a suitable adhesive, one end of a wrapping sheet *b* of paper, this sheet being 45 of suitable length to inclose the tube when the latter is rolled up in it. By means of a sharp instrument, the wall of the tube *a* at some point thereon, is divided in a line parallel with its axis, as at *c*, and at each end of this slit in the wall of the tube, the latter is 50 beveled off, as at *d*, Fig. 3, to the end that

any papers may be easily inserted in the slit there being spring enough in the wall of the tube to clamp these papers with sufficient force to serve as a temporary binder therefor. 55

When the papers are inserted in the slit *c* of the tube, the latter may be rolled up within its wrapper and the free end of the latter secured by any suitable means; preferably, however a piece of soft wire *e* is secured to 60 said free ends of the wrapper by inclosing the wire therein by folding the end of the wrapper thereover and gumming it down to inclose the wire and secure it to the wrapper, the ends of the wire extending far enough 65 beyond the edges of the wrapper to permit them to be folded over and bent into the ends of the tube, as clearly shown in Figs. 1 and 5. While this is the preferred manner of securing the free end of the wrapper to the 70 tube, since it permits the latter to be used more than once, the end of the wrapper may, if desired, be gummed, as shown in Fig. 4 at *f*, and thus provide means for permanently sealing the tube. 75

If desired, the wrapper *b* may be made wider than the tube in order that the opposite borders of the former may be folded into the ends of the tube after the wrapper has been rolled therearound, but this wider 80 wrapper would only be used with the gummed flap, and when the tube was to be used for mailing papers which must be completely inclosed.

What I claim, is:—

1. A mailing tube having a slit therein extending from end to end of the tube parallel with its axis, a wrapper to inclose the tube affixed by one end to the latter, and a metallic strip extending across the free end of 90 the wrapper and secured thereto, the ends of said strip extending beyond the ends of the tube when the latter is inclosed therein, and adapted to be folded into the ends of the tube to secure the free end of the wrapper 95 thereto.

2. A mailing tube having a slit therein extending from end to end of the tube parallel with its axis, the wall of the tube at each end of said slit being cut away to constitute a 100 flaring entrance to said slit, and a wrapper to inclose the tube affixed by one end to the

85

latter and provided with means on the free end thereof to secure said end to the inclosed tube.

3. An article of manufacture comprising a longitudinally slit tube with a flaring entrance portion, a wrapper permanently secured by one of its ends to the external surface of the tube, the other or free end of the

wrapper being provided with means for securing the end of the wrapper to the tube 10 when the wrapper is rolled around the tube, as described.
